UNITED STATES PATENT OFFICE

107,821

DESIGN FOR A TEXTILE FABRIC

Margit Fellegi, Los Angeles, Calif., assignor to West Coast-Manchester Mills Inc., Los Angeles,
Calif., a corporation of California

Application October 30, 1937, Serial No. 72,536

Term of patent 7 years

To all whom it may concern:

Be it known that I, Margit Fellegi, a citizen of the United States, residing at Los Angeles, county of Los Angeles, State of California, have invented a new, original, and ornamental Design for a Textile Fabric, of which the following is a specification, reference being had to the accompanying drawing, forming part thereof. The figure is a plan view of a section of fabric, showing my new design.

I claim:

The ornamental design for a textile fabric, as shown.

MARGIT FELLEGI.
